UNITED STATES PATENT OFFICE

2,418,266

AIR MIXING AND DIFFUSING OUTLET HAVING A CONCENTRIC OPEN ENDED TUBE FOR MIXING ROOM AIR WITH THE INCOMING VENTILATING AIR STREAM

Franz J. Kurth and Friedrich Honerkamp, New York, N. Y., assignors to Anemostat Corporation of America, New York, N. Y., a corporation of Delaware

Application August 16, 1943, Serial No. 498,843

10 Claims. (Cl. 98—40)

1

This invention relates to apparatus for supplying fresh or treated, heated or cooled air to enclosures for heating, cooling, ventilating or other purposes, and has particular reference to improvements in means for the controlled delivery of air from air supply ducts into enclosures for such purposes.

Where there is a temperature differential between the air within an enclosure and the air supplied thereto, it usually is desirable to effect mixing of as much as possible of the enclosure air with as much as possible of the supplied air, as thoroughly as possible, at or in the immediate vicinity of the point of delivery of the supplied air into the enclosure for the purpose of immediately tempering the supplied air with the enclosure air and thereby reducing the possibility of occupants of the enclosure experiencing any sensation of blast, draft or other discomfort. And, of course, the greater the temperature differential between the enclosure air and the supplied air, the more important and desirable such mixing becomes, especially in connection with small enclosures such, for example, as aircraft cabins.

Accordingly, one special and important object of the invention is to provide, in combination with an air supply duct having outlet means for discharge of air therefrom into an enclosure, a simple means whereby discharge of air from the duct through said outlet means effects rapid and thorough mixing of a large amount of the enclosure air with a large amount of the supplied air in the immediate vicinity of the point of discharge of the supplied air from the duct into the enclosure, either for the purpose stated or for any other desired purpose.

At times it may be desirable to supply heated air and at other times it may be desirable to supply cooled air through a given duct to an enclosure, and in either case it may be desirable at certain times to deliver all of the air from the duct in columnar or undiffused form, at other times in outwardly deflected diffused form, and at still other times partly in columnar or undiffused form and partly in outwardly deflected diffused form. Accordingly, another special and important object of the invention is to provide simple, practical control means whereby flow of air from the duct in any of said forms may readily and easily be obtained. Moreover, a further special and important object of the invention in this connection is to combine said air flow control means with the aforesaid air mixing means so that regulation of air flow from the duct regu-

2

lates the amounts of the supplied air and the enclosure air which are intermixed.

With the foregoing and other objects in view, which will become more fully apparent as the nature of the invention is better understood, the same consists in the novel combination and arrangement of elements as will be hereinafter more fully described, illustrated in the accompanying drawings and defined in the appended claims.

In the accompanying drawings, wherein like characters of reference denote corresponding parts in the different views:

Figure 1 is a central, longitudinal section through a portion of an air supply duct and an associated air outlet control means constructed in accordance with one practical embodiment of the invention; and

Figure 2 is a section on the line 2—2 of Fig. 1.

Referring to the drawings in detail, A designates an air supply duct having in a portion 10 of a wall 11 thereof an annular row of openings 12 constituting outlet means for discharge of air from said duct into an enclosure for heating, cooling, ventilating or other purposes, and B designates, generally, a unit, of which the duct wall portion 10 is a part, operatively mounted relative to said duct to control discharge of air therefrom through the openings 12 and under certain conditions, to cause the discharged air to effect intermixture therewith of a considerable amount of the enclosure air for the purpose of tempering the supplied air as it is delivered into the enclosure.

The portion 10 of the duct wall 11 might be an integral part of said wall. Inasmuch, however, as said portion 10 or its equivalent also constitutes an essential part of the unit B, and inasmuch as it is desirable that said unit be complete in itself for association with any duct, it is preferred to form said wall portion 10 as a part of the unit B rather than as an integral part of a wall of the duct so that said unit may be complete in itself and may be operatively associated with any duct simply by cutting an opening in a wall of the latter and by suitably fastening the wall portion 10 to the duct wall in covering relationship to the opening therein. It will be understood, therefore, that even though the wall portion 10 may be a part of the unit B, it is in effect a part of the duct wall 11 when it is operatively fastened thereto.

In the drawings the duct A is presumed to be located at or near the top of an enclosure and is illustrated as being disposed horizontally and as having the outlet openings 12 in the bottom wall 55 thereof for discharge of air downwardly there-

from into the enclosure. It is desired to point out, however, that said duct may be disposed vertically or in any other desired manner and that, regardless of its disposition, any wall thereof may be provided with any suitable outlet means for discharge of air therefrom in any desired direction into an enclosure at any desired point with respect to the enclosure.

In accordance with one feature of the invention, an open-ended tube 13 has one end 13^a thereof disposed to receive enclosure air at any desired point and its other end 13^b disposed in proximity to the openings 12 and facing in the same general direction as the direction of discharge of air from the duct A through said openings, whereby air flowing from said duct through said openings tends to create a negative or lower pressure in the vicinity of the outlet end 13^b of said tube 13 and thereby induces a flow of the enclosure air through said tube. Thus, the enclosure air drawn through said tube becomes intermixed in the immediate vicinity of the openings 12 with the supplied air delivered from the duct through said openings and immediately tempers the supplied air so that its temperature is brought more nearly to the temperature of the enclosure air before it has progressed far into the enclosure, thereby either eliminating entirely or at least materially reducing the possibility of occupants of the enclosure experiencing any sensation of blast or draft due to the temperature differential between the enclosure air and the supplied air.

The relative amounts of the supplied air and the enclosure air that become intermixed depends, of course, upon the relative sizes or cross sectional areas of the openings 12 and the tube 13, upon the velocity of the supplied air delivered through the openings 12 and upon other factors, and in this connection it will be understood, of course, that the openings 12 and the tube 13 may be of any desired sizes or cross sectional areas for flow therethrough and intermixing of any desired relative amounts of the supplied air and the enclosure air.

In the particular example of the invention illustrated in the drawings, the tube 13 is disposed inwardly of and centrally with respect to the annular row of openings 12 and extends through the duct A and has its inlet end 13^a disposed adjacent to the top of said duct and its discharge end 13^b disposed a short distance below the bottom wall 11 of said duct. Obviously, however, said tube 13 may be disposed other than centrally with respect to the row of openings 12 and its inlet end 13^a may be disposed at any other suitable point. Essentially, however, the outlet end 13^b of said tube faces in the same general direction as the direction of discharge of air from the duct A through the openings 12 and is disposed in such proximate relationship to said openings 12 that air flowing from the duct through said openings induces an effective flow of enclosure air through said tube.

In the broader aspects of the invention the means for outlet of air from the duct A may comprise either an annular row of openings 12, as shown, or simply a single opening through or in close proximity to which the discharge end portion 13^b of the tube 13 extends. It is desirable, however, to provide valve means for regulating flow of air from the duct A, and inasmuch as a valve of the apertured disk type is preferred for this purpose, an annular row of openings 12 is provided in lieu of a single opening for cooperation with such a valve.

The row of openings 12 or their equivalent

provide for discharge of air from the duct A in columnar or undiffused form around the discharged end of the tube 13 to induce a flow of enclosure air through said tube, and whenever air is flowing from the duct through said openings 12 or their equivalent it induces a flow of enclosure air through said tube which, in amount, is dependent upon the amount and the velocity of the air flowing through said openings 12 or their equivalent. Thus, for any given velocity of the duct air and a tube 13 of any given cross sectional area, it is manifest that, by varying the effective area of the openings 12 or their equivalent, the amount of the supplied air that is delivered into the enclosure and, consequently, the amount of enclosure air that is drawn through the tube 13 and intermixed with the supplied air and delivered into the enclosure therewith, also is varied. In this connection and as aforesaid, it may be desirable at times either to deny completely or to a greater or lesser extent columnar discharge of air through the openings 12 or their equivalent and to effect discharge of air from the duct through another opening or openings in diffused form. For example, when heated air is supplied through the duct A it usually is desirable to have all or most of this air discharged from the duct through the openings 12 or their equivalent to insure the mixing therewith of a large amount of the enclosure air to rapidly reduce the temperature of the supplied air as it is delivered into the enclosure. On the other hand, when cooled air is supplied through the duct A, it usually is more desirable to have all or a major amount of this air delivered into the enclosure in diffused form rather than columnar form, even though this should mean complete or partial loss of the advantage of intermixing enclosure air therewith.

Accordingly, the wall portion 10 of the duct A is provided with a second row of outlet openings 14 or their equivalent through which all or some of the supplied air may be delivered if desired, and in front of these openings or their equivalent is disposed a flared air deflector ring 15 so that air delivered through said openings 14 or their equivalent is deflected by said ring laterally outward and thereby is delivered into the enclosure in diffused form. Moreover, valve means is provided for completely closing or for varying the effective areas of the openings 14 or their equivalent to regulate the amount of air delivered therethrough, and in this connection it is preferred to employ a single valve of the apertured disk type to regulate flow of air through both rows of the openings 12 and 14, although separate valves individual to said rows of openings or their equivalents may be employed if desired.

In the example of the invention illustrated in the drawings a single valve of the apertured disk type, designated as 16, is employed to regulate flow of air from the duct A through both rows of the openings 12 and 14, and this valve is rotatably mounted upon the wall portion 10 by being marginally confined between said wall portion and the inner marginal portion of a ring 17 which is riveted or otherwise suitably fastened to said wall portion 10 and which constitutes a flange through the instrumentality of which the unit B may readily be fastened to the duct A in operative relationship thereto with the wall portion 10 covering an opening 18 cut in the wall 11 of said duct.

The valve disk 16 may be mounted in any other suitable manner either above or below that portion of the wall portion 10. In any event, said valve disk is provided with two annular rows of openings 19 and 20 which are counterparts of the two rows of openings 12 and 14, respectively.

Between the openings 12 are closed wall portions 21 of approximately the same size and shape as said openings 12, while between the openings 14 are closed wall portions 22 of approximately the same size and shape as said openings 14. Likewise, between the openings 19 are closed valve disk portions 23 of approximately the same size and shape as said openings 19, while between the openings 20 are other closed valve disk portions 24 of approximately the same size and shape as said openings 20. Moreover, the openings 12, 14 are radially aligned and the openings 19 and 20 are radially disaligned, or vice-versa, as may be desired.

Accordingly, if the valve disk 16 is rotated to a position to fully register its openings 19 with the openings 12, its openings 20 are fully closed by the closed wall portions 22 and, at the same time, the openings 14 are fully closed by the closed portions 24 of said valve disk. Therefore, all air will be directed from the duct through the openings 12. If, on the other hand, the valve disk is rotated to a position to fully register its openings 20 with the openings 14, its openings 19 are fully closed by the closed wall portions 21 and, at the same time, the wall openings 12 are fully closed by the closed portions 23 of said valve disk. Therefore, all air will be directed from the duct through the openings 14. Obviously, in any intermediate position of rotation of the valve disk, both rows of the openings 12, 14 will be partly open for flow of air therethrough from the duct, the greater the effective area of the openings of either of said rows the lesser the effective area of the openings of the other of said rows. It follows, therefore, that merely by a small amount of angular adjustment of the valve disk 16, all of the air from the duct A may be required to flow through the openings 12 to induce flow of a maximum amount of enclosure air through the tube 13, or all of the air from the duct may be required to flow through the openings 14 for outward deflection and diffusion by the ring 15, or any desired relative amounts of the air from the duct may be directed through the respective openings 12 and 14, some to induce a certain amount of flow of enclosure air through the tube 13 and the remainder to be deflected and diffused by the ring 15.

In the example of the invention illustrated in the drawings, the air deflector ring 15 is spaced from the wall portion 10 so that when the openings 14 are closed and air is being discharged from the duct through the openings 12, an inward or aspirating flow of the enclosure air is induced through the space between said deflector ring 15 and said wall portion 10, which materially assists in obtaining rapid and thorough intermixing of the enclosure air with the supplied air in the immediate vicinity of the point of discharge of the supplied air. In this connection, a neck or funnel-like member 25 may be employed, if desired, to direct air from the openings 12 toward the discharge end of the tube 13, and a neck or ring 26 may extend forwardly from the inner edge of the ring 15 to assist in inducing a flow of enclosure air through the

space between the ring 15 and the wall portion 10 when all or most of the supplied air is flowing through the openings 12. On the other hand, when air is being discharged through the openings 14 a reverse-direction aspirating flow of air will be induced through the ring 26.

It has been found that by varying the position of the discharge end 13^b of the tube 13 longitudinally relative to the openings 12 or their equivalent in the absence of the funnel-like member 25, or longitudinally relative to said funnel-like member if same or its equivalent is used, the amount of air flow that will be induced through the tube 13 may be varied. Accordingly, 15 in order to provide for longitudinally adjusting the position of the discharge end 13^b of the tube 13, the discharge end portion 13^c of said tube is formed as an element separate from said tube proper and is suitably mounted thereon for longitudinal adjustment with respect thereto, as, for example, through the instrumentality of pins 27 carried by said element 13^c and disposed in inclined slots 28 in the tube proper.

Within the duct A a suitable air deflector element 29, or any desired plurality of such elements, may be provided for directing the supplied air toward and through the openings 12, while in order to prevent supplied air delivered through the openings 14 from too quickly flowing outwardly after passing through said openings, the marginal portion 10' of the wall portion 10 may be directed forwardly any desired distance in any desired form. Moreover, the tube 13 may be provided, if desired, with a suitable damper to regulate flow of air therethrough regardless of adjustments of the valve disk 16.

Any suitable means may be provided for rotatably adjusting the valve disk 16, a handle 30 carried by said disk and extending through a slot 31 in the deflector ring 15 for ready access at the front of the device, being illustrated in the present instance for this purpose.

Without further description it is thought that the features and advantages of the invention will be readily apparent to those skilled in the art, and it will of course be understood that changes in the form, proportion and minor details of construction may be resorted to, without departing from the spirit of the invention and scope 50 of the appended claims.

We claim:

1. In combination, an air supply duct having annular outlet means for discharge of air therefrom into an enclosure, and a tube disposed inwardly of and concentrically with respect to said outlet means for conducting air from the enclosure to a point in proximity to said outlet means for intermixing with and to temper the air discharged from the duct through said outlet means, the outlet end of said tube facing in the same general direction as the direction of discharge of air from said duct through said outlet means and being disposed in such proximity to said outlet means that air flowing through said outlet means from said duct induces a flow of the enclosure air through said tube, said tube including a short length discharge end portion longitudinally adjustable relative to the other portion thereof to vary the position of the discharge end of said tube longitudinally relative to said outlet means, said short-length portion of said tube being spaced a constant distance inwardly from the outer side of said outlet means.
2. In combination, an air supply duct having air outlet opening means for discharge of air

therefrom into an enclosure, a tube for conducting air from the enclosure to a point in proximity to said outlet opening means for intermixture with and to temper the air discharged from the duct through said outlet opening means, the outlet end of said tube facing in the same general direction as the direction of discharge of air from said duct through said outlet opening means and being disposed in such proximity to said outlet opening means that air flowing through said outlet opening means from said duct induces a flow of the enclosure air through said tube, said duct having a second air outlet opening means disposed outwardly of said first mentioned air outlet opening means, means whereby air flowing from said duct through said second mentioned air outlet opening means is deflected laterally outward from said second mentioned air outlet opening means, and means for selectively closing said first and said second mentioned air outlet means against flow of air therethrough from said duct.

3. In combination, an air supply duct having outlet means for discharge of air therefrom into an enclosure, a tube for conducting air from the enclosure to a point in proximity to said outlet means for intermixture with and to temper the air discharged from the duct through said outlet means, the outlet end of said tube facing in the same general direction as the direction of discharge of air from said duct through said outlet means and being disposed in such proximity to said outlet means that air flowing through said outlet means from said duct induces a flow of the enclosure air through said tube, said duct having a second air outlet means disposed outwardly of said first mentioned air outlet means, means whereby air flowing from said duct through said second mentioned air outlet means is deflected laterally outward from said second mentioned air outlet means, and a single element operable to simultaneously decrease the effective area of one and to increase the effective area of the other of said air outlet means.

4. In combination, an air supply duct having inner and outer concentric rows of spaced apart closed portions and openings therebetween for outlet of air from said duct, an open-ended tube having one end in receiving relationship to air exteriorly of said duct and its other end disposed inwardly with respect to the inner row of said closed portions and openings and in proximity thereto and facing in the same direction as the direction of discharge of air from said duct through said inner row of openings whereby air flowing from said duct through said inner row of openings induces a flow of air from the exterior of said duct through said tube for intermixture with the air discharged from said duct through said inner row of openings, means whereby air flowing from said duct through said outer row of openings is deflected laterally outwardly from said outer row of openings, and a rotatable disk valve having inner and outer annular rows of spaced apart closed portions and openings therebetween and disposed for cooperation with the inner and outer rows of spaced apart closed portions and openings of said duct, respectively, to selectively close either of said rows of openings completely or to only partly close both of said rows of openings.

5. The combination as set forth in claim 4 in which the openings of one of the inner rows are radially disaligned from the openings of the related outer row and in which the openings of

5 the other inner row are radially aligned with the openings of the related outer row, whereby continuous rotation of the valve disk in a single direction serves to decrease the effective areas of the openings of one pair of corresponding rows and simultaneously to increase the effective areas of the openings of the other pair of corresponding rows.

6. In combination, an air supply duct having inner and outer concentric rows of spaced apart closed portions and openings therebetween for outlet of air from said duct, an open-ended tube having one end in receiving relationship to air exteriorly of said duct and its other end disposed inwardly with respect to the inner row of said closed portions and openings and in proximity thereto and facing in the same direction as the direction of discharge of air from said duct through said inner row of openings whereby air flowing from said duct through said inner row of openings induces a flow of air from the exterior of said duct through said tube for intermixture with the air discharged from said duct through said inner row of openings, means whereby air flowing from said duct through said outer row of openings is deflected laterally outwardly from said outer row of openings, and a single rotatable valve element operable by rotation thereof to close the openings of either of said rows to the exclusion of the openings of the other of said rows.

7. In combination, an air supply duct having inner and outer concentric rows of spaced apart closed portions and openings therebetween for outlet of air from said duct, an open-ended tube having one end in receiving relationship to air exteriorly of said duct and its other end disposed inwardly with respect to the inner row of said closed portions and openings and in proximity thereto and facing in the same direction as the direction of discharge of air from said duct through said inner row of openings whereby air flowing from said duct through said inner row of openings induces a flow of air from the exterior of said duct through said tube for intermixture with the air discharged from said duct through said inner row of openings, means whereby air flowing from said duct through said outer row of openings is deflected laterally outwardly from said outer row of openings, and a single rotatable valve element operable by rotation thereof to close the openings of either of said rows to the exclusion of the openings of the other of said rows.

8. In combination, an air supply duct having inner and outer concentric rows of spaced apart closed portions and openings therebetween for outlet of air from said duct, an open-ended tube having one end in receiving relationship to air exteriorly of said duct and its other end disposed inwardly with respect to the inner row of said closed portions and openings and in proximity thereto and facing in the same direction as the direction of discharge of air from said duct through said inner row of openings whereby air flowing from said duct through said inner row of openings induces a flow of air from the exterior of said duct through said tube for intermixture with the air discharged from said duct through said inner row of openings, a neck extending from said duct between said two rows of openings and disposed in surrounding spaced relationship to the outlet end portion of said tube, an open-ended hollow member surrounding

said neck in spaced relationship thereto and having its upper end spaced from said duct, a flaring member extending outwardly from said open-ended member to effect outward deflection of air flowing from said duct through said outer row of openings, and a rotatable apertured disk valve operable by rotation thereof to close the openings of either of said rows to the exclusion of the openings of the other row.

9. In combination, an air supply duct having an annular air outlet opening means for discharge of air therefrom into an enclosure, an open-ended tube having one end disposed to receive air from the enclosure and its other end disposed inwardly of and concentric with respect to said outlet opening means and in proximity thereto and facing in the same general direction as the direction of discharge of air through said outlet opening means so that air discharged from the duct through said outlet opening means induces a flow of enclosure air through said tube, said duct having a second annular air outlet opening means disposed outwardly of and concentrically with respect to said first outlet means, and means for controlling flow of air from said duct through each of said outlet opening means.

10. In combination, an air supply duct having an annular air outlet means for discharge of air therefrom into an enclosure, an open-ended tube having one end disposed to receive air from the enclosure and its other end disposed inwardly of and concentric with respect to said outlet means and in proximity thereto and facing in the same general direction as the direction of discharge of air through said outlet means so that air dis-

charged from the duct through said outlet means induces a flow of enclosure air through said tube, said duct having a second annular air outlet means disposed outwardly of and concentrically with respect to said first outlet means, and a single valve means for simultaneously increasing the effective area of one and decreasing the effective area of the other of said outlet means.
